Primary Examiner — Katie Jane Stofko(74) *Attorney, Agent, or Firm* — Michael A. Olshavsky(57) **CLAIM**

The ornamental design of a pet treat, as shown and described.

DESCRIPTION

FIG. 1 is a top isometric view of a pet treat.

FIG. 2 is a bottom isometric view of the pet treat shown in FIG. 1.

FIG. 3 is a front view of the pet treat shown in FIG. 1.

FIG. 4 is a rear view of the pet treat shown in FIG. 1.

FIG. 5 is a side view of the pet treat shown in FIG. 1.

FIG. 6 is another side view of the pet treat shown in FIG. 1.

FIG. 7 is a top plan view of the pet treat shown in FIG. 1; and,

FIG. 8 is a bottom plan view of the pet treat shown in FIG. 1.

The broken lines in the figures are for the purpose of illustrating unclaimed portions of the pet treat and form no part of the claimed design.

1 Claim, 5 Drawing Sheets(56)
